UNITED STATES PATENT OFFICE.

FRANK E. WOLCOTT, OF WEST HARTFORD, CONNECTICUT, ASSIGNOR TO THE FRANK E. WOLCOTT MANUFACTURING CO., A CORPORATION OF CONNECTICUT.

DESIGN FOR AN ELECTRICAL HEATER.

Application filed September 22, 1926. Serial No. 19,144. Term of patent 7 years.

To all whom it may concern:

Be it known that I, FRANK E. WOLCOTT, a citizen of the United States, residing at West Hartford, in the county of Hartford and State of Connecticut, have invented a new, original, and ornamental Design for Electrical Heaters, of which the following is a full, clear, and exact specification when taken in connection with the accompanying drawings, of which—

Fig. 1 is an elevation of an electrical heater, showing my new design;
Fig. 2 is a top plan view of the same, and
Fig. 3 is a bottom view of the casing thereof.

I claim:

The ornamental design for an electrical heater substantially as shown.

In testimony whereof I affix my signature.

FRANK E. WOLCOTT.

CERTIFICATE OF CORRECTION.

Design No. 74,996.

Granted April 24, 1928, to

FRANK E. WOLCOTT.

It is hereby certified that the name of the assignee in the above numbered patent was erroneously written and printed as The Frank E. Walcott Manufacturing Co., whereas said name should have been written and printed as The Frank E. Wolcott Manufacturing Co., as shown by the records of assignments in this office; and that the said Letters Patent should be read with this correction therein that the same may conform to the record of the case in the Patent Office.

Signed and sealed this 5th day of June, A. D. 1928.
